SYNCHRONIZING PULSE GATING SYSTEM

William D. Houghton, Port Jefferson, N. Y., assignor to Radio Corporation of America, a corporation of Delaware.

Application October 18, 1945. Serial No. 623,127

9 Claims. (Cl. 179—1)

This invention relates to a method of and apparatus for "gating" or selecting periodically recurring synchronizing pulses and rejecting all other pulses present during the interval between said synchronizing pulses.

In pulse receiving systems it is known to control the time during which a desired signal pulse is permitted to pass through a vacuum tube. This operation is usually achieved by biasing a tube to cut-off (a condition during which no anode current flows) except for certain time intervals during which the signal pulse is expected to arrive. The tube may normally be cut-off and conditioned to pass the desired signal pulse by supplying to its control electrode a pulse of sufficient magnitude and polarity to overcome the cut-off bias, or in the alternative, the tube may normally be conductive and biased to cut-off during those intervals when signals are not to be passed. Stated in other words, the vacuum tube functions in a manner which is analogous to a "gate" or "shutter" and is "keyed" or "gated" at a desired rate. One such method of "gating" a receiving system, given by way of example, is described in U. S. Patent 2,361,437 granted October 31, 1944 to B. Trevor. Another method is described in copending U. S. application Ser. No. 517,814 filed January 8, 1944 by H. O. Peterson, now U. S. Patent No. 2,463,094, granted March 1, 1949.

The present invention is designed for use in those systems which utilize trains of recurring pulses separated by periodically recurring controlling or synchronizing pulses. The invention finds particular application at the receiving end of a time division multiplex communication system.

In a time division multiplex system, it is customary to generate at the transmitting end of the system short pulses of radio frequency energy and to transmit these pulses at constant amplitude and at a fixed average repetition rate. The pulses in the different channels are transmitted consecutively. These pulses may have their occurrence time or phase modulated within predetermined limits. Thus, a pulse occurs from each channel once for each cycle of operation or synchronizing period, and this pulse is advanced or retarded from its normal time of occurrence by an amount proportional to the instantaneous amplitude of the modulation. During each cycle of operation or synchronizing period, there are transmitted pulses from all of the channels followed by a single synchronizing pulse of longer duration than the channel pulses or by two or

8, 1945, Serial No. 623 127

(CL 179-1)

more short synchronizing pulses more closely spaced in time than the consecutively occurring channel pulses. As an illustration, let it be assumed that there are eight channels. Then during each cycle of operation or synchronizing period, there will occur eight constant amplitude pulses (one for each channel) followed by one or more synchronizing pulses. This cycle of operation repeats itself continuously at the synchronizing period. At the receiving end of the multiplex system, it is necessary to provide a circuit for distinguishing between the channel pulses and the synchronizing pulses. The present invention is a pulse selective system which achieves this purpose and enables the utilization of synchronizing pulses.

One of the objects of the present invention is to provide a "gating" system for the synchronizing pulses in order to prevent interference or mis-
20 synchronizing due to noise, ignition radiation, etc.

Briefly stated, the present invention provides at the receiving end of a pulse communication system, a pulse selective system which distinguishes 25 between synchronizing pulses and channel pulses, and which is "open" or receptive to the synchronizing pulses for only a short period of time compared to the synchronizing period. This "open" or receptive interval occurs at about the time the 30 synchronizing pulse is due to arrive at the receiver station. Because the pulse selective system of the invention is "closed" or non-receptive in the intervals between "open" intervals, noise pulses are prevented from interfering with the 35 synchronizing circuit, and hence, the signal-to-noise ratio is increased compared to other systems where the synchronizing pulse selector is "open" for the entire synchronizing period.

A more detailed description of the invention follows in conjunction with a drawing, wherein Figs. 1, 3 and 4 illustrate three different circuit embodiments of the present invention, and Figs. 2a to 2e are graphical representations of voltage waveforms in different parts of the system, given to aid in an understanding of the operation of the invention.

Throughout the figures of the drawing, the same parts are represented by the same reference characters.

50 Referring to Fig. 1, there is shown one circuit embodiment of a pulse selective and gating system of the invention, comprising a gated pulse vacuum tube amplifier 10 (pentode or mixer type) to whose control electrode the channel and synchronizing pulses are applied, a synchronizing

pulse separator 11, and a gate generator 13.

The pulses supplied to input terminal 9, which is connected to the control electrode of amplifier tube 10 are video pulses of positive polarity and of fixed peak amplitude. It should be understood that these video pulses are unidirectional in character and constitute the output of a superheterodyne or other type radio receiver, not shown.

The amplifier 10 comprises a pentode but may 10 be a mixer type tube such as an RCA 6L7. Amplifier 10 is gated or keyed by pulses applied to its second grid over lead 8 from the output of gate generator 13. If desired, amplifier tube 10 may be a pentode vacuum tube with the screen 15 grid connected as shown in Fig. 3.

The synchronizing pulse separator 11 comprises a dual diode V_2 having two diode sections a and b , a normally conductive triode vacuum tube V_3 forming part of a sawtooth generator, and a normally non-conductive (cut-off) triode vacuum tube V_4 .

The gate generator 13 comprises an electronic trigger circuit in the form of two regeneratively connected vacuum tube triodes V_5 and V_6 having a common cathode bias resistor R_{11} . Tube V_5 is normally conducting and tube V_6 is normally non-conducting in the stable state. The application of a negative pulse to the grid of tube V_5 trips or triggers the circuit into its active state in which the current passing conditions of the two tubes are reversed. The time during which the trigger circuit remains in its active state is determined by the time constants of condenser C_7 and resistor R_8 . The trigger circuit restores itself to the stable state after the charge on condenser C_7 has leaked off.

Output from the trigger circuit in the form of a pulse of negative polarity is taken via coupling condenser C_8 and fed to amplifier 10 over lead 8 in order to bias the amplifier to the anode current cut-off condition.

The anodes of the different tubes in amplifier 10, pulse separator 11 and gate generator 13 are individually supplied with anode polarizing potentials over separate resistors R_2 , R_5 , R_6 , R_9 and R_{10} , respectively, from the positive terminal $+B$ of a source of unidirectional potential.

In the operation of Fig. 1, the normal bias on tube V_1 of the pulse amplifier 10 is set by the values of R_1 and C_2 in the cathode circuit. In the absence of a negative pulse on the second grid (#2) of tube V_1 supplied by the gate generator 13, anode current will flow in this amplifier 10 when the magnitude of the positive video pulses exceeds the cathode bias developed by R_1 and C_2 . These video pulses are of fixed peak amplitude exceeding this cathode bias. In practice, tube V_1 is biased to a negative value by elements R_1 and C_2 so that it conducts at about half amplitude on the incoming pulses. In the normal operation of this amplifier, the voltage on the second grid is reduced during the synchronizing period by the negative pulse on lead 8 supplied from generator 13, to a value which prevents anode current from flowing in tube V_1 . By selecting suitable values for the circuit constants of the electronic trigger circuit of generator 13, this negative pulse on lead 8 terminates immediately before the arrival of a video synchronizing pulse on input terminal 9. The termination of the negative pulse on lead 8 causes the voltage on the second grid of tube V_1 to be raised to zero value which permits anode current to flow in amplifier 10 when an input pulse

is present on the control grid of tube V_1 . After the amplifier 10 has passed the synchronizing pulse or pulses, the voltage on the second grid of tube V_1 is again reduced by a negative pulse on lead 8 to the same low value which prevents anode current from flowing in tube V_1 .

The invention will first be described in connection with a pulse type multiplex system utilizing two closely spaced synchronizing pulses which recur periodically. Pulses from such a multiplex system are represented in Fig. 2a which shows a series of channel pulses followed by two synchronizing pulses for each cycle of operation or synchronizing period. These synchronizing pulses are more closely spaced in time than any two adjacent channel pulses in extremes of modulation. In first starting up the system of Fig. 1, let us assume the absence of a negative pulse on lead 8 for the full synchronizing period since no synchronizing pulse has previously arrived to trip gate generator 13. Before the synchronizing pulse is applied to input terminal 9, tube V_1 will pass anode current each time a channel pulse is applied to its control grid. The flow of anode current in V_1 causes a negative pulse of voltage to be developed across anode resistor R_2 each time a channel pulse is applied to V_1 and this negative pulse is applied to dual diode V_2 through coupling condenser C_1 . The leading (falling) edge of each negative pulse causes the cathode of diode section b of dual diode V_2 to become negative as a result of which current flows in diode section b and produces a negative charge on condenser C_3 . On the trailing (rising) edge of each negative pulse of voltage developed across R_2 , current will flow through section a of dual diode V_2 into condenser C_1 , thus restoring the charge on condenser C_1 to its normal value.

The negative voltages developed across condenser C_3 are shown in Fig. 2b. Condenser C_3 is shunted by a resistor R_4 , and the values of these two elements are such that the negative charge on C_3 leaks off to a low value between channel pulses, as shown in Fig. 2b. However, when two closely spaced synchronizing pulses occur, there are developed two correspondingly closely spaced negative voltages across resistor R_2 which produce cumulatively added negative charges on condenser C_3 . Stated in other words, the negative charge on condenser C_3 due to the first synchronizing pulse does not have an opportunity to leak off to a low enough value to cause anode current flow in tube V_3 before there is added another negative charge on condenser C_3 , caused by the closely spaced second synchronizing pulse. This is shown in Fig. 2b at position A.

Triode V_3 is normally conductive. The anode current cut-off value of tube V_3 is shown by the horizontal dash line in Fig. 2b. It should be observed that tube V_3 is cut-off each time a negative charge is built up on condenser C_3 , but that the duration of cut-off of tube V_3 is over a longer period of time when the two synchronizing pulses are present than when the channel pulses are present. Tube V_3 and condenser C_4 in its anode circuit constitute a sawtooth waveform generator. When V_3 is cut-off, a positive charge builds up linearly on condenser C_4 through resistor R_5 , resulting in a voltage as shown in Fig. 2c. The small pulses in Fig. 2c represent the voltage charges built up on condenser C_4 due to the presence of channel pulses. The larger voltage pulse in Fig. 2c represents the voltage charge built up on condenser C_4 due to the presence of the two

closely spaced synchronizing pulses which causes tube V_3 to be cut off for a longer period of time. Upon the dissipation of the negative charge on condenser C_3 , tube V_3 again conducts and provides a low impedance path to ground for the charge on condenser C_4 .

Tube V_4 is normally non-conducting and the bias is set by resistor R_7 so that it conducts at an amplitude as indicated by the horizontal dash line of Fig. 2c. It will be observed therefore, that tube V_4 conducts only when the synchronizing pulses are present on input terminal 9. When tube V_4 conducts, a negative voltage is developed across resistor R_8 , as shown in Fig. 2d. This negative voltage of Fig. 2d is passed through coupling condenser C_5 and is used to trip the electronic trigger circuit V_5 , V_6 of the gate generator 13, from its stable to its active state.

As mentioned before, tube V_5 is normally conducting and tube 6 normally non-conducting. Tube V_6 is normally non-conducting due to the voltage developed across the common cathode resistor R_{11} by the current flowing therein. Current normally flows in tube V_5 because its grid is connected to $+B$ through resistor R_3 . The application of a negative pulse, Fig. 2d, to the grid of V_5 causes tube V_5 to cut off and allows tube V_6 to conduct. When tube V_6 starts to conduct, there is produced a negative voltage across resistor R_{10} which further biases tube V_5 below cut off, by virtue of the regenerative coupling condenser C_7 . The trigger circuit remains in the active state until the charge on condenser C_7 leaks off through resistor R_8 . Tube V_5 remains cut off, therefore, for a time interval determined by the time constants of condenser C_7 and resistor R_8 . The values of condenser C_7 and resistor R_8 are so chosen that the trigger circuit restores itself to the normal stable state after a time slightly less than the synchronizing period.

As a result of this operation, a negative pulse is developed across resistor R_{10} having a duration slightly shorter than the synchronizing period. This negative pulse is coupled via condenser C_8 and lead 8 to the second or number 2 grid of tube V_1 of the amplifier 10 and keys or "gates" amplifier 10 so that tube V_1 is cut off during the major part of the synchronizing period or for the duration of the negative pulse on lead 8. Hence, amplifier 10 is cut-off during that portion of the synchronizing period when the channel pulses are present. Any noise or ignition interference which might be present on input terminal 9 during the time V_1 is cut off can have no effect on the amplifier 10 of the pulse selective system of the invention and cannot cause mis-synchronization. Obviously, mis-synchronization due to noise is thus confined to the interval when amplifier 10 is "open" or responsive, which occurs just preceding the arrival of the synchronizing pulses. Since noise is random in character and does not recur at the same rate and time as the synchronizing pulses it will be evident that the present invention results in an increase in the signal-to-noise ratio in multiplex systems using pulse type synchronization.

Output pulses from the system of the invention are taken from terminal 14 which is connected to the anode of tube V_4 . These output pulses are of negative voltage as shown in Fig. 2d, and are repeated once for each synchronizing period, and can be utilized to synchronize or control the receiving channel selectors, not shown.

Fig. 2e represents the wave form appearing at the anode of tube V_5 . This is a negative pulse

since V_5 is cut-off and its anode potential is therefore equal to $+B$ up to a time just prior to the arrival of the synchronizing pulse, at which time the gate generator circuit returns to its normal or stable condition. The arriving synchronizing pulse causes tube V_5 to again cut-off and thus drive the flip-flop circuit to its unstable condition. It remains in this state for a period of time slightly shorter than the synchronizing period.

The system of Fig. 1 can also be used satisfactorily in pulse multiplex systems wherein only a single synchronizing pulse of longer duration than the channel pulses is used for each cycle of operation.

Fig. 3 shows a modification of the system of Fig. 1, for use at the receiving end of a pulse multiplex system using a single synchronizing pulse which is of longer duration than the channel pulses. This longer duration synchronizing pulse takes the place of the two closely spaced synchronizing pulses of Fig. 2a, and occurs once for each cycle of operation or synchronizing period.

The system of Fig. 3 is similar to that of Fig. 1 with the exception that the dual diode V_2 of Fig. 1 is eliminated in Fig. 3 and the amplifier tube 10' is a pentode vacuum tube connected somewhat differently from that of Fig. 1. In Fig. 3, the negative pulses developed across resistor R_2 are coupled to the grid of normally conducting tube V_3 via condenser C_1 . Each negative pulse carries tube V_3 to cut off, and as a result causes condenser C_4 to charge up through resistor R_5 . As in Fig. 1, tube V_3 and condenser C_4 form a sawtooth waveform generator. Condenser C_4 charges up to a higher value when the longer duration synchronizing pulse is present because tube V_3 is then cut off for a longer period of time than in the presence of channel pulses. The rest of the system of Fig. 3 operates in the same manner as Fig. 1.

Fig. 4 illustrates another embodiment of the invention in which only triode tubes are employed. This embodiment is also designed for use in such pulse multiplex systems which use a single synchronizing pulse of longer duration than the channel pulses, although by the addition of a diode as in Fig. 1, this embodiment can be used for either system. Fig. 4 includes an additional tube V_7 which is normally biased to the anode current cut-off condition and controlled by a positive output pulse from the trigger circuit V_5 , V_6 via coupling condenser C_9 and lead 1. The grid of tube 7 is supplied with a negative bias via resistor R_{14} and the negative terminal of a unidirectional source of potential $-E$. This negative bias is of such magnitude as to prevent the flow of current through the tube.

The gate generator 13 supplies a positive pulse to the grid of tube V_7 of such magnitude as to overcome the negative bias on tube V_7 and cause this tube to conduct. When tube V_7 conducts, it develops a positive voltage across resistor R_{13} and this positive voltage is supplied via lead 6 to the cathode of tube V_1' , and biases tube V_1' below cut-off for the duration of this positive pulse regardless of the maximum peak amplitude of the video pulses supplied to the grid of V_1' . The video pulses are passed through limiters before being applied to the grid of tube V_1' , hence all pulses are constant amplitude. The duration of this positive pulse (applied to the cathode of tube V_1') is for the major part of the synchronizing period, as in the case of Figs. 1 and 3. The

remaining portions of Fig. 4 operate in the same manner as corresponding portions of Fig. 1.

What is claimed is:

1. In a time division pulse multiplex communication system wherein a plurality of intelligence carrying channel pulses and one or more synchronizing pulses are transmitted during each synchronizing period, a receiving station having apparatus thereat for producing from said received synchronizing pulses other pulses which occur once each synchronizing period, said apparatus including an amplifier multi-electrode tube and means for supplying to said amplifier tube pulses representative of the received intelligence carrying channel pulses and the synchronizing pulses, a circuit coupled to the output of said amplifier for producing voltages of one amplitude in response to the channel pulses and voltages of a higher amplitude in response to the synchronizing pulses, a pulse generator responsive to pulses solely of said higher amplitude, and a feed-back circuit coupling the output of said pulse generator to an electrode of said amplifier, each pulse produced by said generator having such duration, magnitude and polarity as to prevent the flow of current in said amplifier for the major portion of the succeeding synchronizing period.

2. In a time division pulse multiplex communication system wherein a plurality of intelligence carrying channel pulses and one or more synchronizing pulses are transmitted each synchronizing period, a receiving station having apparatus thereat for producing from said received synchronizing pulses other pulses which occur once each synchronizing period, said apparatus including a multi-electrode amplifier tube and means for supplying to said amplifier tube pulses representative of the received intelligence carrying channel pulses and the synchronizing pulses, a circuit coupled to the output of said amplifier for producing voltages of one amplitude in response to the channel pulses and voltages of a higher amplitude in response to the synchronizing pulses, an electron discharge tube coupled to the output of said last circuit and normally biased to be non-conductive, said tube being responsive only to voltages of said higher amplitude in order to pass current, an electronic trigger circuit coupled to and responsive to the flow of current in said electron discharge tube for producing a pulse, and a feed-back circuit from said trigger circuit to an electrode of said amplifier, the pulse produced by said trigger circuit having such duration, magnitude and polarity as to prevent the flow of current in said amplifier for the major portion of the succeeding synchronizing period.

3. In a time division pulse multiplex communication system wherein a plurality of intelligence carrying channel pulses and one or more synchronizing pulses are transmitted each synchronizing period, a receiving station having apparatus thereat for producing from said received synchronizing pulses other pulses which occur once each synchronizing period, said apparatus including a multi-electrode amplifier tube and means for supplying to said amplifier tube pulses representative of the received intelligence carrying channel pulses and the synchronizing pulses, a circuit coupled to the output of said amplifier for producing voltages of one amplitude in response to the channel pulses and voltages of a higher amplitude in response to the synchronizing pulses, an electron discharge device coupled to the output of said last circuit and normally biased to be non-conductive, said tube being responsive only to

voltages of said higher amplitude in order to pass current, a self-restoring electronic trigger circuit coupled to and responsive to the flow of current in said electron discharge device for producing a pulse, and a feed-back circuit from said trigger circuit to an electrode of said amplifier for feeding back to said amplifier a pulse which prevents the flow of current in said amplifier, the time constants of said trigger circuit being such that it supplies said feed-back circuit with a pulse whose duration extends over the major portion of the synchronizing period.

4. In a time division multiplex system for receiving periodically recurring controlling or synchronizing pulses between which are positioned intelligence carrying pulses, apparatus for converting said synchronizing pulses to other pulses which occur once each synchronizing period, said apparatus including a multi-electrode vacuum tube and means for supplying to said tube pulses representative of the received intelligence carrying pulses and the synchronizing pulses, a triangular waveform generator coupled to the output of said tube for producing triangular-shaped voltage waves of one amplitude in response to the intelligence carrying pulses and triangular-shaped voltage waves of a higher amplitude in response to the synchronizing pulses, a pulse generator circuit responsive solely to the voltage waves of said higher amplitude for producing substantially flat-top pulses, and a feed-back circuit from said pulse generator circuit to an electrode of said tube for feeding back to said tube a pulse which prevents the flow of current in said tube, the time constants of said pulse generator being such that it supplies said feed-back circuit with a pulse whose duration extends over the major portion of the synchronizing period.

5. In a time division multiplex system for receiving periodically recurring synchronizing pulses between which are positioned intelligence carrying pulses, apparatus for converting said synchronizing pulses to other pulses which occur once each synchronizing period, said apparatus including a multi-electrode vacuum tube and means for supplying to said tube pulses representative of the received intelligence carrying pulses and the synchronizing pulses, a triangular waveform generator coupled to the output of said tube for producing triangular-shaped voltage waves of one amplitude in response to the intelligence carrying pulses and triangular-shaped voltage waves of a higher amplitude in response to the synchronizing pulses, a pulse generator, and electronic means responsive to each wave of higher amplitude produced by said triangular waveform generator for tripping said pulse generator, and a feed-back coupling, the output of said pulse generator to an electrode of said tube, the pulses produced by said pulse generator having such duration as to extend over the major portion of the synchronizing period.

6. In a pulse selective system, a multi-electrode amplifier tube, means for supplying to the input of said tube recurring trains of pulses in each train of which at least one pulse is of different character than the others in that train, a diode having its cathode coupled to the output of said amplifier tube, a condenser connected between the anode of said diode and ground, a resistor in shunt to said condenser, a normally conducting triode having its grid connected to the anode of said diode and its cathode connected to ground, a resistor connecting the anode of said

triode to the positive terminal of a source of unidirectional potential, a condenser connected between the anode of said triode and ground, said triode and last condenser forming a sawtooth generator, another triode normally biased to the anode current cut-off condition, a resistor connecting the anode of said last triode to said positive terminal, a connection from the grid of said last triode to the anode of said first triode, a pulse generator coupled to the anode of said last triode, and a feed-back circuit from the output of said pulse generator to an electrode of said amplifier for supplying said amplifier with pulses of such magnitude and polarity as to cut off the flow of current in said amplifier, the duration of the pulse produced by said pulse generator extending over the major part of the time occupied by said train of pulses.

7. In a time division pulse multiplex receiving system, an amplifier tube, means for supplying to the input of said tube recurring trains of pulses in each train of which there are a plurality of intelligence carrying pulses and a synchronizing pulse of different character than said intelligence carrying pulses, a triangular waveform generator means coupled to the output of said amplifier, means for causing said triangular waveform generator to produce a triangular-shaped voltage wave of higher amplitude for each said synchronizing pulse in the train than for the intelligence carrying pulses in the train, an electronic circuit responsive solely to the triangular voltage wave of higher amplitude for producing a substantially flat-top wave pulse, and a feed-back circuit from said electronic circuit to said amplifier tube, the pulse in said feed-back circuit having such magnitude, polarity and duration as to prevent the flow of anode current in said amplifier tube for the major part of the period occupied by a train of pulses.

8. In a time division pulse multiplex communication system wherein a plurality of intelligence carrying channel pulses and one or more synchronizing pulses are transmitted each synchronizing period and are repeated, a receiving station having apparatus thereat for producing from said received synchronizing pulses other pulses which occur once each synchronizing period, said apparatus including a multi-electrode amplifier tube having a screen grid and means for supplying to said tube pulses representative of the received intelligence carrying channel pulses and the synchronizing pulses, a circuit coupled to the output of said amplifier for producing volt-

ages of one amplitude in response to the channel pulses and voltages of a higher amplitude in response to the synchronizing pulses, a pulse generator responsive to pulses solely of said higher amplitude for producing correspondingly positioned pulses, and a feed-back circuit coupling the output of said pulse generator to the screen grid electrode of said amplifier tube, each pulse produced by said pulse generator being of negative polarity and of such duration as to prevent the flow of current in said amplifier tube for the major portion of the succeeding synchronizing period.

9. In a pulse multiplex communication system wherein a plurality of channel pulses and one or more synchronizing pulses are transmitted each synchronizing period and are repeated, a receiving station having apparatus thereat for producing from said received synchronizing pulses other pulses which occur once each synchronizing period, said apparatus including a multi-electrode amplifier tube to which are applied pulses representative of the received pulses, said amplifier tube including a cathode, a circuit coupled to the output of said amplifier for producing voltages of one amplitude in response to the channel pulses and voltages of a higher amplitude in response to the synchronizing pulses, a pulse generator responsive to pulses solely of said higher amplitude, and a feed-back circuit coupling the output of said pulse generator to an electrode of said amplifier, said feed-back circuit including a triode whose cathode is connected to the cathode of said amplifier for supplying to said amplifier a pulse of positive polarity and of such magnitude and duration as to prevent the flow of current in said amplifier for the major portion of the succeeding synchronizing period.
